EDWARD B. GOODALL, OF PORTSMOUTH, NEW HAMPSHIRE.

Letters Patent No. 85,653, dated January 5, 1869.

IMPROVED MODE OF INSERTING ARTIFICIAL TEETH.

The Schedule referred to in these Letters Patent and making part of the same.

To all whom it may concern:

Be it known that I, EDWARD B. GOODALL, of Portsmouth, in the county of Rockingham, and State of New Hampshire, have invented a new and improved Mode of Constructing and Inserting Partial or Whole Sets of Artificial Teeth, which I shall call "Goodall's Elastic or Spring-Plate;" and I do hereby declare that the following is a full, precise, and exact description thereof, reference being had to the accompanying drawings, in which—

Figure 1 represents a view of the roof of the mouth, or a cast thereof, with the front teeth or incisors removed.

Figure 2 is a view of two artificial front teeth, secured in or to a plate constructed in accordance with my invention.

Figure 3 is a view of the cast shown in fig. 1, with the plate shown in fig. 2 inserted.

The nature of my invention consists in making plates of an elastic or springy material, and of such shape or form that, while adapting itself to the form of the mouth, it will be held in its place when inserted in the mouth, by its elasticity, *i. e.*, without clasps or suction, and this is accomplished by cutting away from plates, as ordinarily made of an elastic substance, the roof or upper part thereof, leaving wings or spring-like arms, or by forming the plate holding the artificial teeth of an elastic strip, fitting the sinuosity of the roof of the mouth, at or near that part of the mouth which corresponds to the roots of the teeth, substantially as shown in the drawings.

To enable others to make and use my said invention, I shall now proceed to describe the manner in which the same is or may be carried into effect.

After obtaining the plaster-cast of the mouth, in the manner heretofore practised, I cut out from the portion of the plaster-cast which corresponds to the roof of the mouth, more or less, according to the shape of the mouth, for the formation of wings of requisite form and thickness or elasticity. Then, if rubber be used for the base, I take a pure and highly-elastic compound, and pack it in its plastic condition, as usual, and vul-

canize it until the plate becomes hard and elastic. By heating the plate so vulcanized, I can shape it to obtain a greater or less degree of elasticity at pleasure.

In connection with the elastic plate, such as described, another improvement may be used, *viz.*, a bevel-edge on the palatal surface of the plate of partial sets, and posterior surface of whole sets, which embeds itself into the mouth. The bevel-edge is made by cutting, with a knife, the palatal surface of the cast about one-sixteenth of an inch, more or less, according to the sponginess of the mouth, and by then packing the plate (if of rubber) as usual.

I sometimes festoon the plate when packed, before vulcanizing to the cast and necks of the teeth, down near to the cast, so as to leave them projecting from the plaster the thickness of the plate to be used, so that it will fit exactly to the neck of each of the natural teeth, and be held in position by the elasticity of the plate, as aforesaid.

To secure the plate in the mouth, it is only necessary to slightly compress it, by placing the thumb on one arm or wing of the plate, and the fore-finger on the other, and setting the plate in its proper place and releasing it. The plate will be thus securely and firmly held, and none of the discomforts attending clasps will be felt, while nausea or impaired taste, or defective speech, or food working under the plate, which more or less attend the use of all other plates, will be effectually obviated.

Claim.

Artificial dentures, composed of elastic or spring-like plates, having artificial teeth inserted therein, or secured thereto, such plates being held in their places by elastic pressure, as herein described, in contradistinction to suction or clasps, by which dental plates were heretofore held and secured.

EDWARD B. GOODALL.
